UNITED STATES PATENT OFFICE.

PAUL E. SCHWARZ AND THOMAS D. SALMON, OF PHILADELPHIA, PENNSYLVANIA.

CASTING MACHINE.

1,424,595.

Specification of Letters Patent. Patented Aug. 1, 1922.

Application filed March 23, 1922. Serial No. 546,193.

To all whom it may concern:

Be it known that we, PAUL E. SCHWARZ and THOMAS D. SALMON, citizens of the United States, residing in Philadelphia, 5 Pennsylvania, have invented Casting Machines, of which the following is a specification.

Our invention relates to devices particularly designed for making dental and similar 10 castings, and one object of said invention is to provide a simple, reliable, comparatively inexpensive device for causing air pressure to be applied to a body of molten metal, with a view to causing this to flow into a 15 suitably positioned mold.

It is further desired to provide a casting machine of the above type which shall include a novel form of supporting structure for the molds or investment rings, particularly 20 designed to receive any of several rings of different dimensions.

We also desire to provide a casting machine including a cylinder and piston, with means for automatically locking said piston 25 in the position in which it is moved in order to cause pressure to be applied to a body of molten metal, so that there shall be no possibility of back flow of air or of the formation 30 of air bubbles until after the metal has solidified.

Our invention further contemplates novel means for preventing solid material passing to the interior of the cylinder, together with means whereby such foreign material may 35 be conveniently removed from a pocket in which it is permitted to collect.

These objects and other advantageous ends we attain as hereinafter set forth, reference being had to the accompanying drawings, in which,

The figure is a longitudinal vertical section of a casting machine constructed in accordance with our invention.

In the above drawings 1 represents a cylinder casting having a laterally extended supporting base portion 2, one end of the cylinder being permanently closed and the other having a removable head 3. Within said cylinder is mounted a closely fitting piston 4 having connected to it a piston rod 5 which extends through a central opening in the head 3 and has its outer end pivotally connected to an operating lever 6. The lower end of the latter is pivotally connected 55 to one end of a link 7, which in turn is pivotally connected to the base 2 of the cylinder

casting, and said lever is extended upwardly above the piston rod, having its upper end shaped as a hand hold 8 to permit of its convenient operation. The opposite or permanently closed end of the cylinder has an integral boss 9 formed adjacent its upper portion and this is formed with a vertically extending, substantially cylindrical cavity 60 opening through a passage 10 into the upper 65 part of the cylinder. The lower end of this passage is normally closed by a conveniently removable plug 11 and its upper end has threaded or otherwise attached to it a cup 12 formed with a central, vertically extending 70 passage 13 opening into the cylindrical cavity of the boss 9.

Concentric with this passage are a series of plane annular faces 14, 15 and 16 arranged in stepped relation and designed for 75 the reception of the corresponding plane lower faces of investment rings or molds of different diameters, the cup having an upwardly extending peripheral flange 17. Within the cylindrical cavity of the boss 9 80 is mounted a cylindrical wire screen 18 conveniently removable after the plug 11 has been removed, and the arrangement is such that this screen not only effectually prevents solid matter entering the passage 10, but also 85 is positioned to collect such solid material or particles in its lower part below the entrance to said passage.

The head 3 of the cylinder has formed in it an air relief passage 19 from the interior 90 of the cylinder and in the present instance we have formed in line with a portion of this passage a cavity in which is operable a plunger 20 whose lower end is designed to enter a recess 21 in the piston rod 5 when 95 this has been moved to a position in which the piston 4 is immediately adjacent the head 3. This plunger is at all times pressed toward the piston rod by a spring 22 and has on its outer end, which projects above the top 100 of the cylinder head, a cap or head 23 to permit of its being drawn upwardly against the action of its spring.

Under conditions of use an investment ring or equivalent structure containing or 105 carrying a mold, is mounted in the cup 12 so that its lower face engages and makes substantially air tight contact with one of the flat faces 14, 15 or 16. With the piston in the position illustrated in the drawing, a 110 body of metal is melted upon or immediately adjacent said mold and when said metal is

at the right temperature, the operating handle 6 is drawn to the left until the plunger 20 enters the recess 21 in the piston rod. The resulting movement of the piston rod 5 exhausts the air from the right hand end of the cylinder so that the atmospheric pressure acting on the molten metal forces it into a suitably prepared opening in the mold and into the cavity or cavities thereof. Obviously the plunger 20 locks the piston in its given position so that there is no possibility of back pressure upon the mold from the cylinder which might form air bubbles in the casting.

During the above described operation of the piston the air otherwise confined between it and the head 3 escapes through the passage 19 so that it does not interfere with the operation. Any particles of solid material drawn into the passage 13 are caught in the cavity of the boss 9 from which they may be removed from time to time by removing the plug 11; the screen 18 effectually preventing such particles from passing into the cylinder. When desired for further operation the piston is released by drawing out the spring plunger 20, after which it may be returned to the position shown in the drawing, ready for another stroke.

It is particularly to be noted that the above described device is relatively simple and rugged in construction and does not include or require valves of any kind. For this and other reasons it is reliable and capable of producing uniformly perfect castings, having no tendency to get out of order and being easily cleared, as above described.

We claim:

1. The combination in a casting machine 40 of a cylinder casting including a hollow box communicating with the interior of the casting; a mold-supporting cup mounted on said

box having a passage communicating with the cavity thereof; a removable plug closing the lower part of said cavity; a screen in 45 the cavity for preventing solid material passing into the cylinder casting; a piston in the cylinder casting; and means for actuating said piston.

2. The combination in a casting machine 50 of a cylinder having a box connected to its interior and formed with a cylindrical cavity therein; a substantially cylindrical screen in said cavity positioned to prevent solid material passing into the cylinder; a plug 55 normally closing the cavity of said box; a mold-supporting structure having a passage connected to said cavity; a piston in the cylinder; and means for actuating said piston.

3. The combination in a casting machine 65 of a horizontally extending cylinder having a removable head; a piston in the cylinder; a rod connected to said piston and passing through the head; a handle connected to the rod for actuating the piston; a hollow box 70 formed to constitute a trap at one end of and communicating with the upper part of the cylinder; a closure for an opening into the box and a cup for a dental mold removably mounted on and having a passage connected to the interior of said box.

4. The combination in a casting machine 75 of a cylinder casting including a hollow box communicating with the interior of the casting; a mold-supporting cup mounted on said box having a passage communicating with the cavity thereof; a screen in the cavity for preventing solid material passing into the cylinder casting; a piston in the cylinder 80 casting; and means for actuating said piston.

PAUL E. SCHWARZ.
THOMAS D. SALMON.
